UNITED STATES PATENT OFFICE.

MICHAEL I. PUPIN, OF NORFOLK, CONNECTICUT, ASSIGNOR TO WESTINGHOUSE ELECTRIC AND MANUFACTURING COMPANY, OF EAST PITTSBURGH, PENNSYLVANIA, A CORPORATION OF PENNSYLVANIA.

EQUALIZING VACUUM-TUBE AMPLIFIER.

Application filed December 23, 1918. Serial No. 268,044.

To all whom it may concern:

Be it known that I, MICHAEL I. PUPIN, a citizen of the United States, residing at Norfolk, in the county of Litchfield, State of Connecticut, have invented certain new and useful Improvements in Equalizing Vacuum-Tube Amplifiers; and I do hereby declare the following to be a full, clear, and exact description of the invention, such as will enable others skilled in the art to which it appertains, to make and use the same.

This invention relates to vacuum tube amplifiers, and involves a method and apparatus by means of which the amplifying power of vacuum tube amplifiers are equalized, so that these tubes can replace each other, particularly in a balanced multi-step amplifier system.

Commercial vacuum tube amplifiers, while seemingly identical, often, and generally, have slight structural inequalities which affect their amplifying action or power. The amplifying actions of such commercial tubes thus generally differ, so that it is usually impracticable to directly replace, in any balanced amplifying system, one vacuum tube by another. The aim of the present invention is to provide a method of and means for equalizing the amplifying action of such tubes, so that one tube can be readily and conveniently replaced by another tube, without unbalancing the system. In carrying out the method of the invention, I first determine the amplifying action of each of the tubes which it is desired to equalize. This determination I prefer to make by use of a wave balance, such as described in my co-pending application for Letters Patent of the United States, Serial No. 257,570, filed October 10, 1918, upon which Patent No. 1,456,909 was granted May 29, 1923. These determinations, preferably visualized by suitable curves, indicate the magnitude and character of the inequalities in amplifying action of the various tubes. I then relatively adjust, taking one tube at a time, the potential relations of the electrodes of these tubes, until the amplifying actions of all of the tubes, over the desired range of operation, are substantially equivalent. By determining and noting the adjustment made with each tube to produce the desired am-

plifying action, I am able to predetermine, in the case of each tube, just what adjustment must be made in the potential relations of its electrodes whenever one tube is to be replaced by another in a balanced amplifying system. 55

While various ways of adjusting the potential relations of the electrodes of a vacuum tube amplifier will occur to those skilled in the art, I prefer to make this adjustment by varying the potential difference between the grid electrode and the hot electrode or filament of the tube. To this end, I have found it advantageous to include a resistance in the filament circuit, and to provide means for inserting in the grid electrode circuit variable amounts of this resistance. This resistance may be a permanent element of the system, and by suitably graduating the same, and by using it in equalizing the various vacuum tubes under such conditions of operation as normally prevail in the system, the vacuum tubes may be calibrated in terms of the graduations of the resistance, so that in replacing one tube by another, it is only necessary to adjust the resistance as indicated by the calibration of the tube to be placed in the system. 75 80

The novel features of the invention which I believe to be patentable are definitely set forth in the appended claims. These features, together with the arrangement and mode of operation of apparatus embodying the same, will be best understood from the following description, taken in conjunction with the accompanying drawings, in which; Fig. 1 represents diagrammatically an arrangement of apparatus for modifying the amplifying action of a vacuum tube amplifier; Fig. 2 represents diagrammatically the use of a wave balance for determining the amplifying action of a vacuum tube amplifier connected as indicated in Fig. 1; Fig. 3 diagrammatically represents one unit in a balanced amplifier system in which the equalizing apparatus of the present invention is employed; and Fig. 4 illustrates certain curves which represent the amplifying actions of three vacuum tube amplifiers. 90 95 100

Referring to Fig. 1 of the drawings, there is diagrammatically represented a low impedance vacuum tube amplifier having a

grid electrode 10, a hot electrode or heating filament 11 and a plate electrode 12. A local source of direct current electric energy, such, for example, as a battery 13, serves 5 to supply the relatively low voltage, say about seven volts, for maintaining a filament current of about 1.3 amperes, and the relatively high voltage, say about 100 volts, for 10 the wing or electron current between the filament 11 and the plate 12.

The plate electrode 12 is connected to the positive terminal of the battery 13 through a suitable inductance coil 14. One terminal of the filament 11 is connected to the positive terminal of the low voltage section 15 of the battery 13, while the other terminal of the filament is connected through a resistance or rheostat 15 to a common ground connection 16. The heating current for 20 the filament 11 thus passes through the conducting wire of the resistance 15.

The resistance 15 is provided with a scale graduated in suitable units. A sliding or adjustable contact 17 serves to connect any 25 point of the resistance 15 to the grid 10, and thus places the grid at any desired potential below the potential of the filament.

As is well known, the lower the potential of the grid with respect to the potential of 30 the filament, the higher will be the effective internal impedance of the vacuum tube and, the external impedance and the plate potential being fixed, the lower will be the amplifying power of the tube. It is obvious then that if the potential of the plate electrode 12 is fixed, say 100 volts, and the heating filament current, as well as the other elements in the structure represented in Fig. 1, are fixed, then the motion of the movable 35 contact 17, by varying the potential of the grid electrode 10, will vary the amplifying power of the tube. In this manner, the amplifying action of a vacuum tube can be very readily modified, in order to render its 40 amplifying power substantially equivalent to the amplifying power of a second vacuum tube.

Fig. 2 of the drawings diagrammatically represents the procedure described in my 45 aforementioned copending application for using a wave balance in determining the amplifying action of a vacuum tube arranged as represented in Fig. 1. Corresponding elements of these two figures are 50 indicated by the same reference numerals. The wave balance comprises inner and outer laminated layers of tin-foil 18 and 18' respectively, between which is positioned a coiled wave conductor 19, separated by suitable di-electric layers from each tin foil 55 layer. The wave conductor has substantially uniformly distributed inductance and capacity and possesses sufficiently high resistance and capacity to make it a true wave 60 conductor and to render it practically a pe-

riodic. The secondary coils 20 and 21 of the wave balance are inductively associated with the wave conductor 19 and are relatively movable with respect to each other and to the wave conductor. The foregoing 70 elements of the wave balance are diagrammatically indicated in Fig. 2 of the drawings.

The "beginning" of the wave conductor 19 is connected to one terminal of a source 75 of alternating electromotive force 22, while the "end" of the wave conductor is connected to the common ground 16. The terminals of the secondary coil 20 are connected by a suitable resistance 23. This resistance should be large in comparison with the impedance of the secondary coil. The resistance 23 has an adjustable contact or terminal 24, and functions in effect as a non-inductive potentiometer. The adjustable 80 contact 24 is connected to the grid 10. One terminal of each of the secondary coils 20 and 21 is connected to the common ground 16. The ungrounded terminal of the secondary coil 21 is connected to the plate electrode 12 through a condenser 25 and the primary winding of a transformer 26. The secondary winding of the transformer 26 is connected to a heterodyne receiver, indicated generally by reference numeral 27. 85 By means of the adjustable contact of the potentiometer 23, a suitable fraction of the voltage induced in the secondary coil 20 is impressed upon the grid 10 and is reproduced in amplified form at the plate 12, and 90 will there produce an alternating current through the primary winding of the transformer 26, condenser 25, secondary coil 21 to ground and back to the plate 12. When, 95 however, the electro-motive force induced in the secondary coil 21 is of opposite phase and of equal amplitude, no current will flow in the circuit just mentioned, and the heterodyne detector will be silent. This silence is, however, produced by adjusting the amplitude of the electro-motive force impressed 100 upon the grid 10 and by moving the secondary coil 21 until the phase relation is 105 properly adjusted so as to produce silence in the detecting telephone. The amplifying power of the vacuum tube amplifier is then calculated from the potential impressed upon the grid and from the position 110 of the secondary coil 21 by means of the attenuation curve of the wave balance for the 115 frequency under consideration.

In accordance with the present invention, the amplifying power of each of the tubes which it is desired to equalize, is measured in the manner described in the preceding paragraph. In this manner, the three curves represented by A, B and C in Fig. 4, were obtained. These three curves represent what may be termed the characteristic amplifying curves of three low impedance 120 125 130

vacuum tubes A, B and C. The amplifying power of each tube was measured by the wave balance, as hereinbefore described, for various potentials from 90—150 volts of 5 the plate electrode 12. In determining the amplifying power of these three tubes, an arrangement of apparatus such as illustrated in Fig. 2 was employed, and the movable contact 17 was maintained, in each 10 case, on scale division 21. Each of the three curves A, B and C of Fig. 4, thus bear the legend "SD 21." The filament current in these tubes was normal; that is, 1.3 amperes. The total resistance of the rheostat or 15 resistance 15 was 3.5 ohms, so that at scale division 21, which is somewhat less than one-quarter of the whole rheostat arc, the potential difference between grid and filament was approximately .95 volts.

20 Curves A, B and C clearly show that the amplifying powers of these three tubes differ very considerably under the conditions specified hereinbefore, and, therefore, they cannot replace one another in a balanced 25 multi-step amplifier, such, for example, as described by the applicant in his co-pending application Serial No. 257,571, filed October 10, 1918, upon which Patent No. 1,452,933 was granted April 24, 1924. What 30 is true of these three tubes, which were selected at random, is generally true of all vacuum tube amplifiers.

Curves A', B' and C' of Fig. 4 were obtained for the same three vacuum tubes, 35 in the manner diagrammatically indicated by Fig. 2, with the movable contact 17 suitably adjusted, in each case, to render the amplifying action of the three tubes, over a desired range of operation, as nearly 40 equivalent as possible. Thus, curve A' was obtained by placing the movable contact 17 at scale division 99, which put the grid of the tube A at relatively low potential with respect to the filament and thus diminished 45 the amplifying power of this tube. The characteristic amplifying curve of this tube was thus transformed from curve A to curve A'. In a similar manner, the characteristic amplifying curves for the other 50 tubes B and C were transformed into the curves B' and C' by placing the movable contact 17 at scale division 66 and at scale division 25, respectively. The three curves A', B' and C' coincide at the plate potential of 100 volts and for a considerable interval above and below 100 volts. For that interval these tubes can replace each other. Some other interval can be selected just as well. I have found that by far the greatest 55 number of reasonably good tubes of this type can be made equivalent to each other by adjusting the voltage of the grid with respect to the voltage of the filament (the so-called C voltage), in the manner just 60 described.

The manner of utilizing this method of equalizing the amplifying action of vacuum tubes is diagrammatically represented in Fig. 3 of the drawings. In this figure, the vacuum tube and its associated parts, previously described, are indicated by the same reference numerals as hereinbefore used to designate corresponding elements. A wave balance, of which the wave conductor and tin-foil layers are symbolically represented by reference numerals 19' and 18", respectively, has the wave conductor 19' thereof connected through a blocking condenser 30 to the plate electrode 12 of the vacuum tube. The secondaries 20' and 21' of the wave balance are connected in series with an adjustable capacity 31 and a high resistance conductor 32, as described in my copending application, Serial No. 257,571, (Patent No. 1,452,933) aforementioned. The movable 85 contact 17 connects a suitable point, the point of equivalency for the vacuum tube under consideration, of the resistance or rheostat 15 to the grid electrode 10 through the high resistance 32. When the amplifying system represented by Fig. 3 is adjusted according to the principles described in my copending application, last referred to, it will stay so adjusted when the vacuum tube 90 amplifier 10—11—12 is replaced by another amplifier made equivalent to it by moving the contact 17 to a predetermined point of the resistance 15, which operation adjusts the voltage of the grid 10.

From the foregoing description, it will 100 be observed that my present invention involves a determination of the amplifying action of the vacuum tube amplifier to be equalized under substantially similar predetermined conditions of operation, and then an adjustment of the potential relations of the electrodes of these tubes until the amplifying action of the tubes, over a desired range of operation, are substantially equivalent, and finally a determination 105 of the character of such adjustments, so that the same may be reproduced at will. While I prefer, in producing the desired adjustment of the potential relations of the electrodes of the vacuum tubes, to adjust the potential of the grid electrode with respect to the filament, other ways of effecting the desired adjustment of the electrode potentials may be used, as, for example, by inserting in the plate circuit 110 a suitable resistance, and by its variation varying the plate voltage. However, I prefer to adjust the potential of the grid electrode with respect to the filament because it affords the possibility of running 115 a multi-step amplifier in which each tube has the same plate voltage and in which the same filament current is obtained for each tube by making the resistance of the various wing inductances (14) the same, and the 120 125 130

resistance of all rheostats (15) the same. In this manner, one voltmeter suffices to indicate the voltage of each plate and one ammeter suffices to control the currents in 5 the various filaments.

I claim:

1. The method of measuring the amplifying power of a three-electrode vacuum tube which consists in deriving two periodic 10 electromotive forces of opposite phase from a common source of periodic energy, applying a measured adjustable fraction of one of said electromotive forces between the grid and cathode, applying the other of 15 said electromotive forces between the anode and cathode, detecting the presence of periodic current in the anode-cathode circuit, and adjusting said fraction until said current is nil.
- 20 2. The method of adjusting a three-electrode vacuum tube having a resistance in series between the filament and the negative end of the A- battery and a connection

from an adjustable point in said resistance to the grid, which consists in deriving two 25 periodic electromotive forces of opposite phase from a common source of periodic energy, applying a measured adjustable fraction of one of said electromotive forces between the grid and filament, applying the 30 other of said electromotive forces between the anode and filament, detecting the presence of periodic current in the anode-cathode circuit, and adjusting said fraction until said current is nil, computing the 35 amplifying power of the tube from said measurements, changing the adjustment of said point and repeating said measurements, doing the same with different plate voltages, selecting from the several sets of 40 measurements the position of said point which gives the desired amplification power over a selected range of plate voltage and adjusting said point to said position.

In testimony whereof I affix my signature.

MICHAEL I. PUPIN.
